UNITED STATES PATENT OFFICE

OLIVER S. BOWMAN, OF COLORADO SPRINGS, COLORADO

FLOOR CONSTRUCTION

Application filed April 7, 1930. Serial No. 442,218.

This invention relates to improvements in floor constructions and has reference more particularly to an improved construction of cement floors of the general type described and claimed in my copending applications, Serial Nos. 413,774 and 413,775, filed on December 13, 1929.

It is the object of this invention to produce a floor of fireproof or semi-fireproof construction having a surface composed of concrete or like durable materials, divided into anchored and correlated sections in a manner which permits it to flex with the joists or other cushioning means of support.

The above and other objects that may become apparent as this description proceeds are attained by means of the construction and arrangement of parts that will now be described in detail and for this purpose reference will be had to the accompanying drawings in which the preferred embodiment of the invention has been illustrated and in which:

Fig. 1 is a plan view of a portion of a floor constructed in accordance with my invention, portions of the concrete being removed so as to better disclose the construction;

Fig. 2 is a detail showing the manner of applying the separator strips;

Fig. 3 is a section taken on line 3-3, Fig. 1;

Fig. 4 is a section taken on line 4-4, Fig. 3;

Fig. 5 is a section similar to that shown in Fig. 3, but with the wooden joists and showing a slightly modified form of construction;

Fig. 6 is a section taken on line 6-6, Fig. 5;

Fig. 7 is a section similar to that shown in Fig. 4 and shows another modification;

Fig. 8 is a section showing my floor supported on a concrete slab; and

Fig. 9 is a section taken on line 9-9, Fig. 8.

In the drawing reference numeral 1 designates the floor joists which have been shown as formed from I-beams of ordinary construction and numeral 2 designates the

pans that are supported on the I-beams and which in turn form supports for the concrete. The pans are made from sheet metal and are each of considerable length. The pans can be of any suitable length and are usually a multiple of the distance between the joists so that the joint between any two adjacent pans will come on top of a joist. One such joint has been designated by reference numeral 3 in Fig. 1. The pans are usually of the same width as the distance between the joists in the construction where they are used and have their sides turned up as indicated by reference numeral 4. The upper edges of sides 4 are preferably bent downwardly and lie on the inside of the sides as indicated by reference numeral 5. The lower edges of the bent down portions form shoulders that serve to hold the concrete in place in a manner that will hereinafter more clearly appear. For the purpose of securing the pans to the joists, the bottoms of the pans have been provided with integral tongues 6 that can be bent downwardly about the edges of the upper flange of the joists in the manner shown in Fig. 3. After the joists have been put in place, the pans can then be put in place on the joists and secured to them in the manner shown. To permit the hard surface of the floor to flex with the joists without cracking and becoming loose, it is necessary to divide the concrete into sections and anchor them to the supporting base, which is accomplished by means of the unique separator strips and the vertical sides of the pans. In the present construction one of these separator strips has been designated by reference numeral 7 and this strip is placed between the two adjacent vertical sides 4 of adjacent pans in the manner shown in Figs. 2 and 3. The strips 7 are usually held against removal by means of screws or pins 8 in the manner shown in Fig. 3, and 7 are provided with spaced notches 9 that extend downwardly from their upper edges and which are adapted to receive strips 10 that extend at right angles to them. The strips indicated by reference numeral 10 have notches 11 that are adapted to receive the

sides 4 of the pans in the manner shown in Fig. 4. The notches 9 and 11 are of such depth that when strips 10 are put into place, their upper edges are on the same level as the upper edges of strips 7, as shown in the drawings. After the separator strips have been put in place, the rectangular spaces or compartments are then filled with a suitable concrete mixture, which may either be trowel finished, as are ordinary concrete floor surfaces; or, when suitable materials are used, as in terrazzo or like floors, then the surface is ground and finished in the usual manner.

In Figs. 5 and 6 I have shown a slightly modified form of construction in which the turned down edges 5 of sides 4 have been omitted. Instead of placing the separator strip 7 between the two sides of the adjacent pans, the sides themselves are placed in contact with each other and are held together by means of a separator 12 which is provided on its lower side with a slot 13 into which the upper edges of sides 4 extend in the manner shown in Fig. 6. Screws 14 serve to hold separators 12 in place and extending transversely of the pans are separators 15 whose upper edges are widened as indicated at 16 so that their width is equal to the width of separators 12. Separators 16 are provided with notches 17 that receive the sides 4 in the manner shown. The separators 15 are provided with openings 18 and the same is also true of separators 10. These openings permit the concrete to extend through the separators thereby anchoring them in place. The separators 12 are preferably cut of such length that they fit the space between the separators 16 in the manner shown in Fig. 5.

In Fig. 7 I have shown another modification and in this modification the pans are provided with upwardly extending sides 19 and 20. Sides 19 have a width equal to the thickness of the finished floor and are provided with longitudinal grooves 21. The sides 19 are also provided with spaced notches extending downwardly from the upper edge thereof and which in turn receive the separator plate 7. The opposite side of each pan is narrower than sides 19 and is provided with an outwardly bent portion 22 that fits against the inner surface of groove 21, as shown in Fig. 7. Grooves 21 serve to anchor the concrete block or sections and the concrete that passes through openings 18 serves to hold the separators 7 in place.

It will be seen from the above description that I have produced a floor construction of great simplicity that can be very easily installed and which forms a substantial floor when in place.

In Fig. 1 the joists 1 have been shown as composed of steel I-beams, but this is illustrative only and instead of steel, wooden

joists can be used in which case the pans are provided with holes for the reception of nails by means of which they are attached to the joists, all as shown in Fig. 5.

In Figs. 8 and 9 I have shown my improved floor supported on the upper surface of a concrete slab 23 and are spaced from the latter by means of strips 24 of fibrous material and which will yield slightly when subjected to pressure. The pans are provided with sides 4 that are straight instead of having their upper edges folded downwardly as indicated by 5 in Fig. 4. The separator strips 7 are located between adjacent sides 4 as shown in Fig. 9 and are held in place by bolts 8. Holes 18 are provided for anchoring the concrete floor sections.

Having described the invention what is claimed as new is:

1. A floor construction comprising parallel floor joists, elongated pans extending transversely of the joists and supported thereon, the sides of the adjacent pans being placed adjacent each other with their edges extending upwardly and notched separator strips extending transversely of the pans.

2. A floor construction comprising, in combination, spaced parallel floor joists, long shallow pans having sides extending upwardly substantially at right angles to the bottoms, the bottoms of the pans having downwardly extending lugs for anchoring the pans to the joists and separator strips extending transversely of the pans.

3. A floor construction comprising, in combination, spaced parallel floor joists, long shallow pans provided with parallel sides extending upwardly at right angles to the bottoms, means for attaching the pans to the joists, a separator strip associated with each pair of adjacent sides and separator strips extending across the pans at spaced intervals.

4. A floor construction of the class described comprising spaced, supporting joists, elongated pans supported on the joists, each pan having a flat bottom and upwardly extending edges, the bottoms of the pans having a plurality of pairs of downwardly extending lugs that constitute means for securing the pans to the joists, separators located between adjacent pans, means for securing the separators to the sides of the pans and separators extending across the pans for cooperating with the sides of the pans and with the other separators for forming rectangular recesses for the reception of concrete.

5. In a floor construction of the type described, pans for supporting the concrete floor on the joists, said pans being formed from metal sheets whose edges are bent into parallel spaced planes that lie at right angles to the planes of the bottoms of the sheets, one of the sides being higher than the

other and provided with a groove extending its entire length, the higher side being also provided with spaced notches.

6. In a floor construction of the type described, pans for supporting the concrete floor on the joists, said pans being formed from metal sheets whose edges are bent into parallel spaced planes that lie at right angles to the planes of the bottoms of the sheets, one of the sides being higher than the other and provided with a groove extending its entire length, the lower side having its free edge bent so that it will fit the wall of the groove in the wider side member.

10 7. In a floor construction of the type described, pans for supporting the concrete floor on the joists, said pans being formed from metal sheets whose edges are bent into parallel spaced planes that lie at right angles to the planes of the bottoms of the sheets, one of the sides being higher than the other and provided with a groove extending its entire length, the lower side having its free edge bent so that it will fit the 15 wall of the groove in the wider side member, the higher side having spaced notches for the reception of transverse separators.

20 In testimony whereof I affix my signature.
